UNITED STATES PATENT OFFICE.

HARRY H. BURSON, OF CHICAGO, ILLINOIS, ASSIGNOR TO SIMPLEX STEEL PRODUCTS COMPANY, OF CHICAGO, ILLINOIS, A CORPORATION OF ILLINOIS.

CLIP FOR PLASTER BOARDS AND THE LIKE.

1,417,793.

Specification of Letters Patent. Patented May 30, 1922.

Application filed July 31, 1920. Serial No. 400,498.

To all whom it may concern:

Be it known that I, HARRY H. BURSON, a citizen of the United States, residing at Chicago, in the county of Cook and State of Illinois, have invented certain new and useful Improvements in Clips for Plaster Boards and the like, of which the following is a specification.

This invention relates to a clip of the kind which is commonly employed in the construction of fire proof walls, and is particularly concerned with certain improvements in the means for holding together the adjacent edges of boards of plaster or analogous material preparatory to the application of plaster thereon.

The objects of this invention are to provide a simple and inexpensive clip which may be readily formed from sheet metal, and which in use may be easily applied to securely hold the plaster boards in proper alignment and spaced relation. Other objects and uses will also appear from the detailed description to follow wherein reference is made to an exemplification of my invention as illustrated in the accompanying drawing which exhibits in Figure 1 a perspective of three plaster boards installed between studdings, two of the present clips being shown in operative position, and in Figures 2 and 3 plan and perspective views, respectively, of the clip per se.

To clearly show the manner in which this clip is used, there is represented in the drawing a studding A from which are bent tongues 5, the free end of each being gripped around a pin 6 which engages the outer side of a plaster board B so as to hold it firmly against the studding. Between each pair of studdings these plaster boards are positioned in some such fashion as this, the boards being juxtaposed one against the other, edge to edge, their number depending upon the length of the studding. The present clips C are arranged between the edges of adjoining plaster boards, as shown, for purposes of alignment and reinforcement, as well as for spacing, as will now be explained.

Each clip is preferably stamped from sheet metal to provide a body on which are carried a plurality of wings 7 and 8 arranged, respectively, in two courses, each of which is disposed in a plane that is spaced from the other, but parallel thereto. The wings in one course are furthermore stag-

gered in their relation to those in the other course, and all of them are formed integral with the clip body which consists in part of webs 9 extending between the wings and intermediately of their ends, as shown. As viewed in plan, the clip presents a zigzag structure with the wings in one course spaced apart from those in the adjacent course a distance approximately equal to the thickness of a plaster board.

In the use of these clips the wings are required to lie flat upon opposite sides of the plaster boards, each wing engaging with its opposite ends a different board. Through the medium of the webs 9 which present their opposite edges to adjoining boards, these plaster boards are also maintained in spaced relation. In this manner each board is preserved in alignment with the one adjacent thereto and derives support therefrom to withstand lateral pressure. When the plaster is applied it may freely enter the space between the boards and partially slop over to their inner sides, thus forming a plaster key.

From the preceding description, it will be observed that my clip requires only a small amount of metal for its manufacture. It may be readily installed in place so as to provide an effective medium for aligning as well as spacing the plaster boards. Accordingly in respect of such features of invention as are incorporated into the present clip structure, whether or not made in the exact form shown, I desire to be protected in this patent, the invention being herein claimed as follows.

I claim:

1. A clip of the kind described comprising a plurality of wings arranged in double courses, the wings in the two courses being adapted to present their inner faces flatly against the opposite sides of a plaster board, and means connecting the said wings formed integral with them all and comprising webs extending obliquely from a wing in one course to a proximate wing in the other course, and vice versa in zigzag formation throughout the length of the clip, the webs being disposed edgewise between the edges of the plaster boards against which the wings are presented to thereby space said plaster boards apart an appreciable distance, substantially as described.

2. A clip of the kind described comprising

a body of sheet metal bent in zigzag fashion and adapted to present its edges between the edges of a pair of juxtaposed plaster boards to thereby space them apart a definite distance, a plurality of wings formed integral with the clip body in double courses, one on each side of the two plaster boards, the wings being extended from the clip body in opposite directions to engage with both 10 plaster boards, substantially as described.

3. A clip of the kind described comprising a body of undulating sheet metal arranged

to present its edges between the edges of a pair of juxtaposed plaster boards to thereby space them apart a definite distance, and 15 wings extended in opposite directions from the undulations on the clip body to lie upon opposite sides of each of the two plaster boards to thereby retain them in place, substantially as described.

HARRY H. BURSON.
